UNITED STATES PATENT OFFICE.

JOHN R. PAYNE, OF FREEDOM, INDIANA.

DRAG-SAW.

SPECIFICATION forming part of Letters Patent No. 297,841, dated April 29, 1884.

Application filed March 18, 1884. (No model.)

To all whom it may concern:

Be it known that I, JOHN R. PAYNE, a citizen of the United States, and a resident of Freedom, in the county of Owen and State of Indiana, have invented certain new and useful Improvements in Sawing-Machines; and I do hereby declare that the following is a full, clear, and exact description of the invention, which will enable others skilled in the art to 10 which it appertains to make and use the same, reference being had to the accompanying drawings, which form a part of this specification, and in which—

Figure 1 is a side view of my improved sawing-machine. Fig. 2 is a similar view of the same, seen from the other side. Fig. 3 is a top view, and Fig. 4 is a detail view.

Similar letters of reference indicate corresponding parts in all the figures. 20 My invention has relation to that class of sawing-machines in which the power to reciprocate the saw is derived from a person rocking a lever having handles and foot-rests at its opposite ends with his hands and feet; and 25 it consists in the improved construction and combination of parts of the same, as herein-after more fully described and claimed.

In the accompanying drawings, the letter A indicates a rectangular frame, the top pieces, 30 B B, of which extend beyond the ends of the frame, and form handles by means of which the machine may be transported from place to place, and form transverse bearings C near the rear end of the frame, in which rocks a 35 transverse shaft, D, upon which the hand and foot lever E is secured at its middle, which lever is provided with a foot-rest, F, at its lower end, and with a transverse handle, G, at its upper end, by means of which the lever 40 may be rocked by a person sitting in the seat H, which is secured in the rear end of the frame. A pitman, I, is hinged at one end to the lower end of the hand and foot lever, and is hinged at its other end to a double crank, 45 J, upon a shaft, K, journaled in transverse bearings L L in the sides of the frame, which shaft is provided with a cog-wheel, M, at one end, which meshes with a pinion, N, secured upon a shaft, O, journaled in transverse bearings P in the sides of the frame, and provided

upon one end with a fly-wheel, Q, and with a crank, R, at the other end. A pitman, S, is hinged to the crank, and is hinged or pivoted adjustably at its other end to the rear end piece, T, of a rectangular frame, U, sliding 55 in horizontal ways V, formed upon the outer sides of the top piece and bottom piece of that side of the frame, allowing the end of the pitman to be raised or lowered. The outer side of the rear end piece of this rectangular sliding frame is provided with a flange, W, T-shaped in cross-section, upon which flange a block, X, having a T-shaped recess, Y, slides, and may be adjusted by means of a set-screw, Z. The rear end of the saw-bearing bar A' is 65 pivoted to this block, and the saw B' is secured in the end of the saw-bearing bar, and has the corners of its lower toothed edge rounded, so as not to drag objects upon the ground if the frame is moved and the saw is 70 not raised. The outer portion of the saw-bearing bar slides in the lower end of a long frame, C', provided with an anti-friction roller, D', at its lower end, upon which the saw-bearing bar slides, and is secured upon the end of 75 a bar, E', pivoted at its rear end upon the upper side piece of the frame upon a bolt, F'. A lever, G', is secured upon the inner or rear end of the frame-bearing bar, and is provided with a pawl, H', operated by means of a handle and rod, I', which pawl engages a ratchet-segment, J', upon the top piece of the frame. Two dogs, K', are hinged to the forward end 80 of the frame, and two rods, L', slide in bails upon the rear uprights, M', of the frame, having their upper ends bent at a right angle, adapting them to rest upon two pegs, O', upon the inner sides of the uprights when the rods 85 are raised.

It will be seen that the frame may be secured 90 upon the ground by forcing these rods into the ground, and that the log or wood-jack or saw-horse may be held by the dogs; and it will also be seen that the saw may be lowered or raised by means of the lever and the frame-bearing bar, while the angle of the saw while sawing may be adjusted by sliding the block having the T-shaped recess upon the flange of the rear end piece of the rectangular sliding frame. 95

Having thus described my invention, I claim and desire to secure by Letters Patent of the United States—

In a machine for sawing, the combination of 5 a reciprocating frame having its rear end piece provided with a flange T-shaped in cross-section, a block having a recess T-shaped in section and sliding upon the flange, and provided with a set-screw, a saw-bearing bar 10 hinged to the said block, and a bar having a frame at its forward end provided with an

anti-friction roller at its lower end adapted to have the saw-bearing bar sliding upon it, and having means for raising or lowering the bar, as and for the purpose shown and set forth. 15

In testimony that I claim the foregoing as my own I have hereunto affixed my signature in presence of two witnesses.

JOHN R. PAYNE.
